UNITED STATES PATENT OFFICE.

RICHARD J. EVANS, OF VAN WERT, OHIO.

LACING DEVICE.

No. 904,416.

Specification of Letters Patent.

Patented Nov. 17, 1908.

Application filed May 18, 1907. Serial No. 374,335.

To all whom it may concern:

Be it known that I, RICHARD J. EVANS, a citizen of the United States of America, residing at Van Wert, in the county of Van Wert and State of Ohio, have invented new and useful Improvements in Lacing Devices, of which the following is a specification.

This invention relates to lacing devices designed more particularly for use with leggings, and one of the principal objects of the same is to provide a lacing device which will hold the legging closely to the leg of the wearer, and which will not have any projecting portions outside the legging to catch on obstacles and annoy the wearer.

Another object of the invention is to provide a lacing device comprising tubular lace bearings upon one flap of the legging, and intermediately disposed, alternately arranged lacing hooks secured to the other flap of the legging with the bills of the hooks disposed inward or on the inside of the flap.

Still another object of the invention is to provide a lacing device for leggings in which the shank or projecting portions of the tubular bearings or lacing hooks are extended to provide stiffening means for the edges of the flaps to prevent the legging from wrinkling or falling upon the leg of the wearer.

These and other objects may be attained by means of the construction illustrated in the accompanying drawing, in which:

Figure 1 is a side view of a legging provided with a lacing device made in accordance with my invention. Fig. 2 is a detail sectional view on the line 2-2, of Fig. 1. Fig. 3 is a similar view on the line 3-3, of Fig. 1. Fig. 4 illustrates, in plan view, the tubular lace bearing and the lacing hook member at the upper part of the legging. Fig. 5 is a similar view showing a plurality of tubular lace bearing members formed on a shank or base plate, and a plurality of hooks also secured to a single shank or base plate to be used in a lacing device for the legging. Fig. 6 is a detail elevation showing the lacing or cord and tying cord tied together at the upper end of the legging.

Referring to the drawing for a more particular description of my invention, the numeral 1 designates a legging which may be of the usual or any suitable construction and provided with a lacing flap 2 at one edge thereof, and a similar flap 3 at the op-

posite edge thereof. Connected to the flap 3 is a series of lacing tubes 4 having flaring outer edges 5 to prevent abrasion of the lacing. The lacing tubes 4 are formed integral with the shank or base plate 6 provided with rivet holes 7.

As shown in Fig. 5, two of the lacing tubes 4 are formed upon a single shank 6 provided with rivet openings 7, these lacing tubes having flaring outer edges 5. The hooks 8, two of which are formed on a single base plate 13 are provided with flaring outer edges, and the base plate is provided with rivet holes 14. This form of lace bearing may be used for the purpose of giving a certain amount of stiffening to the lacing flaps of a legging.

Secured to the flap 2 near the upper end thereof is a lacing hook 8, the bill 9 of which is disposed inwardly or located upon the inner side of the flap, while immediately back of the bill is a slight depression 10 to prevent the lacing from withdrawal. The tubular portion 11 of the hook is also provided with flaring edges 12, and said hook is formed integral with a base plate 13 provided with rivet holes 14. To cover the heads of the rivets, a tongue or flap c is secured to the inside of flap 3, as shown in Fig. 2. In securing these lace bearings to the legging strips of leather 16 may be used to prevent the lacing devices from being pulled out and to also serve as a reinforce for the flaps 2 and 3. A lacing cord 17 is secured to the flap 2 by means of a knot 18, said cord passing through an eyelet 19 at the lower edge of the legging, passed through the tubular lacing bearings, and engaged by the hooks so that the upper end of the lacing cord may be drawn tightly to bring the two flaps together, as shown in Fig. 1. To unfasten the legging the hooks 8 are unhooked without detaching the lacing. A tying cord 20 is secured to an eyelet 21 at the upper end of the legging, and designed for the purpose of tying with the cord 17 to prevent withdrawal of the same from the lacing device.

From the foregoing it will be obvious that a lacing device made in accordance with my invention does not project beyond the legging, and is not provided with projections; is neat in appearance; serves to hold the legging firmly to the leg of the wearer; can

be quickly attached and detached; and can be manufactured at comparatively slight cost.

Having thus described the invention, what I claim is:

- The combination with a legging, of a lacing device comprising a series of lacing tubes having flaring outer edges, an integral base plate for each of said tubes, a series of lacing hooks having flaring outer edges and integral base plates, said tubes and hooks being secured upon the inner sides of the flaps of the legging with the hooks arranged

intermediate the tubes, the bills of the hooks being disposed upon the inside of the flap of 15 the legging, and said tubes and hooks being disposed beyond the edges of the flaps, and a lacing cord extending through said tubes and engaged by said hooks.

In testimony whereof, I affix my signature 20, in presence of two witnesses.

RICHARD J. EVANS.
